WIRE NETTING MACHINE

Frank Bergandi, Los Angeles, Calif.

Application September 16, 1946, Serial No. 697,187

5 Claims. (Cl. 140—92.6)

1

This invention relates to a machine for forming flat helical coils of wire such as used in fence wire netting and the like.

It is the object of my invention to provide a device capable of simultaneously forming successions of pairs of such wire coils of predetermined length. It is a further object to provide within the device means adjustable to vary the lengths of coils as may be required.

These and other objects of the invention will be better understood from the following detailed description and by referring to the accompanying drawings, of which:

Fig. 1 is a side elevational view of a device embodying the invention;

Fig. 2 shows, in perspective, the form of mandrel employed for the wire forming operation;

Fig. 3 is a detail view of the cut-off mechanism of the device;

Fig. 4 is a plan view of the left end portion of Fig. 1;

Figs. 5, 6 and 7 are end views taken respectively on lines 5, 6 and 7 of Fig. 4;

Fig. 8 is a fragmentary end view of a portion of Fig. 4;

Fig. 9 is a side elevational view of the parts of Fig. 8;

Fig. 10 is a fragmentary plan view of the wire feeding mechanism of the device; and

Fig. 11 is a side view of a portion thereof.

In the form illustrated in the drawings, the device of my invention includes, generally, a wire forming section A, a cut-off mechanism B, a device C for twisting together the projecting ends of the two newly formed adjacent wire coils, and an operating and control mechanism D for the aforementioned devices.

Two strands of wire *a, b*, are fed between groups of rollers *1, 2* to a mandrel *10*, and these rollers are mounted on frames, each of which comprises two plates *4, 5*. One of the plates of each frame is hung on a pivot *6* for relative adjustment to maintain the strands *a, b* under any required tension. A handscrew *7* is provided to clamp the plates together in adjusted position.

The mandrel *10* consists of a flat bar which, at the inner end thereof, is twisted, substantially as indicated at *10a*, for the purpose of facilitating the forming of the two strands into flat, helical coils. On the machine frame is mounted a block or cradle *11*, the upper surface of which is grooved to receive a cylindrical guide *12*, and this guide is clamped in position in the cradle by means of screws *13, 14*. The strands of wire are, during rotations of the mandrel, forced to fol-

low the windings of the guide and they advance therefrom in the form of flat, uniformly spaced helical coils. When the two coils have advanced the desired, predetermined distance, it is found that the mandrel stops and that, at the same time the cutting mechanism *B* is actuated. All of the foregoing will be hereinafter more fully described.

The device by means of which the operation of the coil winding and cut-off mechanisms is controlled will now be described. The mandrel *10* is seated in the inner end of a shaft *20*, to which is rigidly secured a spiral gear *21*. A jackshaft *22* carries a gear *23* in mesh with the gear *21* and a smaller spiral gear *24*, at the opposite end of the shaft, is in permanent mesh with a large gear *25*, of a timing shaft *26*, for rotating the latter at a relatively much slower speed.

To the shaft *26* is rigidly secured a clutch member *27*, and a second clutch member *28* is hung for rotation on the shaft. A spring *29* urges the member *28* into engagement with the member *27* for simultaneous rotation in clockwise direction. A third shaft *30* is mounted parallel with the aforementioned shafts *20, 26*, and this shaft is, in a manner which will be described later, connected to operate the cut-off and wire twisting mechanisms. In operation, the mainshaft *20* is rotated to form the two coils of wire, whereupon it is stopped for an instant and the shaft *30* is rotated during this brief period to perform its function. The control mechanism necessary for this purpose will now be described.

In an annular, internally recessed groove *28a* of the clutch member *28* are seated an upper stop *31* and a lower stop *32*, which stops are clamped in position on the member by means of bolts *33*. The upper stop is shown offset to the left, the offset portion thereof resting on a stationary anvil *34* of the machine frame. The lower stop is offset to the right for contact with a stud *35* of an arm *36* when the shaft *26* is rotated in clockwise direction. The arm *36* is hung on a pivot *37* and a spring *38* urges this arm downward.

To a shaft *40* is secured a vertically rising frame *41* and a horizontally extending arm *42* (see Fig. 8), and a powerful spring *43* extending from the machine frame to the outer end of the latter urges counterclockwise rotation of this shaft. The arm *36* is notched, substantially as indicated at *36a*, in Fig. 5, and the upper end of the frame *41* is shown recessed to receive the notched portion of the arm, thereby to maintain it in upright position against the tension of the spring *43*.

A clutch 45 connects the drive gears of the machine with the shaft 20, and this clutch is fitted with a lever 46 which, through a rock frame 41, a roller 48 of this frame, and a link 49 which rides on a stud 44 of the arm 42, is operatively connected to be swung counterclockwise, thereby to release the clutch.

It was above stated that the timing shaft 26 rotates clockwise slowly, thereby to cause the stop 32 to rise until it reaches the end of the stud 35. Continued movement causes the arm 36 to rise until the shoulder 36^a thereof leaves the recess bottom of the frame 41, which latter thereupon by the spring 43 is caused to swing to the left. It is now noticed that the lower end of the lever 46 is inwardly directed to form a cam surface 46^a, along which the roller 48 travels when the rock frame 41 is tilted by the downwardly moving arm 42, thereby to release the clutch 45.

On the shaft 40 is rigidly mounted an arm 50, the upper end of which engages the outer end of a bellcrank 51 to cause the latter to swing on its pivot 52 and so to withdraw the clutch member 28 from the fixed member 27. As best shown in Fig. 5, a counterweight 53 is so hung on the member 28 that it will return this member to its initial position the moment the member is released.

A clutch connects the shaft 30 with the driving mechanism of the machine and it comprises a member 60 which is rigidly mounted on a sleeve of the shaft. The second clutch member 62 rides on a feather 63 of the shaft, and a bellcrank 64 is pivotally secured at 65 to a fixed bracket 66 of the machine frame. A spring 67 urges movement of this bellcrank in clutch closing direction. The clutch is, however, normally maintained in open position in the following manner.

As best shown in Figs. 4, 6 and 7, a rocker 70 is hung on a shaft 71 and it is, by means of a link 72, connected for operation by the frame 41. One end of this rocker is fitted with gear teeth 70^a in mesh with the teeth of a rack bar 73 which is guided within a frame 74, vertically rising from and forming part of the rocker. A laterally projecting button 74^a of this frame contacts a stud 75 of the bellcrank 64 normally to maintain the latter and the clutch member 62 retracted. However, when arm 41 is released to open the main shaft clutch, as above described, it is found that the rocker 70 is oscillated, thereby to cause the rack bar 73 to slide downward and the head 73^a of this bar to pass below the high point 76^a of a cam 76. The latter is rigidly secured to the shaft 30. The spring 67 is now free to swing the bellcrank 64 and to move the clutch member 62 to carry the clutch into closed position and thereby to cause the shaft to rotate. Before, however, one rotation is completed, it is found that the cam 76^a will reach and pass the head of the rack bar, in passing to force it outward.

It is now noticed that a second cam 77 is secured to the shaft 30 (see also Fig. 5), and this cam engages the upper end of an arm 78 which, by a link 79, is connected with the upper end of the frame 41. It is important to note that this cam commences to swing the arm 78 thereby to return the frame 41 to its initial position to close the main shaft clutch at the same time that the cam 76 commences to push the rack bar outward. Also that, because the rocker 70 is connected with the frame 41, this rocker is swung back into its initial position further to insure complete withdrawal of the clutch member 62 and to effect return, rising movement of the rack bar. A

spring 69 may be added to further this return movement.

Precision of timing is essential to successful operation of my machine. It is for this reason necessary to employ the toothed clutches on the shafts 26 and 30. No difficulty is encountered in releasing the clutch of the timing shaft 26, because the pressure against the rising stop 32 is so light. I have found, however, that the clutch of the shaft 30 may tend to stick and I have, for this reason, provided means for overcoming such tendency. Such means is shown in the form of an arm 80, rising from the bottom of the machine and fitted at the top with a roller 81 which engages a notch in a cam 82 of the shaft 30. A powerful spring 83 urges the roller into this notch. The bottom face 82^a of the cam notch is slightly downwardly inclined and this is done in order to compel the roller, the moment it passes over the high point of the cam, by the tension of the spring 83, in a flash to pass over and depress the cam surface, thereby for an instant to accelerate the rotating movement of the shaft and so to relieve any pressure tending to cause the clutch teeth to stick.

Additional adjustment of the various features of the machine is provided for the purpose of the delicate timing of the various operations thereof. It is, for example, important that the stud 75 is correctly set in order that the arm 41 may be moved to effect the opening of the timing clutch at the correct moment. A small fraction of one second would suffice to leave the finished coils out of alignment with the cut-off mechanism and the wire end twisting elements. But when the stud is threaded into the bellcrank 64, as shown, such critical adjustment may readily be effected.

It was above stated that the stops 31, 32, of the timing clutch, are clamped in set position by bolts 33. The upper stop 31 remains permanently in the position chosen and the fine adjustment required to raise the arm 36 so as to free it from the arm 41 at the critical moment may be effected by rotating the stud 35. Once correctly set, this stud is rigidly locked in position by the check nut 39. The stop 32, on the other hand, is movable along the periphery of the timing clutch a distance corresponding to the width of netting to be produced.

As above stated, the mandrel 10 is somewhat twisted near one end thereof, and this is done in order more positively to bring the flattened coils of the wire strands into continued alignment. Where a straight mandrel is used, it is found that the resilience of the wire will tend to unwind each coil as it leaves the mandrel, but the sudden twist imparted to the wire as it passes over the twisted portion of the mandrel, overcomes this tendency. The harder the wire used, the greater the tendency to unwind, and it is for this reason preferable to keep on hand mandrels correctly shaped to suit the kind of wire used.

The general idea of using a solid helical guide to form the coils of the netting is old in the art, but I have found that the wire mesh produced in such solid guide is not always uniformly spaced, the minutest variations in the caliber or the texture of the wire coils as they come from the manufacturer causing sufficient variations in the lengths of coils produced to affect or even prevent successful cutting and end twisting operations.

The guide 12 of the present invention is not, however, solid but consists of two identical, heli-

cal coils 15, 16, which are independently mountable in the groove of the cradle 11 by means of the screws 13, 14, see Fig. 1. When the perforations of the cradle, through which the screws extend, are elongated as shown, it is seen that one coil may be slightly adjusted relative to the other, and both coils may be adjusted relative to the twist in the mandrel. The guide may, in such manner, readily be set to produce perfect coils.

I have found it advantageous to place a second helical guide a distance behind the guide 12. This second guide is similarly composed of identical, helical coils 90, 91, which are independently fastened in the cradle 94 by screws 92, 93. In case a very slight variation in the linear spacing of the coils of one of the strands of wire, or both, is found, it is a simple matter by slight adjustment of these additional guides to overcome this difficulty.

In addition, it is to be noted that the cradles are mounted on a slide 95 which is movable lengthwise on the machine frame in order correctly to position the helical coils relative to the cut-off and the wire twisting mechanisms after one coil has been adjusted relative to the other. A bolt 96 is provided to clamp on the slide rigidly in adjusted position.

The wire twisting mechanism is merely indicated at C, such mechanism being commonly used in devices of this type and may be of any suitable preferred construction.

The mandrel is mounted in a chuck 17, which is rotatably adjustable within an annular guide 18 of the shaft 20 and clamped in position by bolts 19. This adjustment is important in the mounting of the mandrel, the main outer part of which, when the machine reaches wire cutting position, must assume a vertical position.

The cut-off mechanism is, in Fig. 3, shown to comprise slides 100, 101, which are hung on a rail 102 and are fitted at the top thereof to support cutting tools 103, 104. To a shaft 105 are secured eccentrics 106, 107, from which extend straps 108, 109 to the lower ends of the slides. As indicated in Fig. 4, a gear pinion 110 is fastened to the mandrel shaft 20 and it is in permanent mesh with a larger gear 111 of the shaft 30. These gears and shafts are driven by an electric motor through the medium of belts 112 which ride in grooves of the clutch member 45. The shaft 105 is, in Fig. 3, shown connected for rotation from the shaft 30 by means of a sprocket wheel 113 and chain 114.

When the clutch 45 is released to permit the mandrel shaft 20 to stop for the purpose of the cut-off and the wire twisting operations, it is found that the tension stored in the newly made double coil within and between the two sets of helical guides exerts a powerful backlash pressure against the mandrel and the shaft 20. This pressure would rotate the mandrel and the shaft in the opposite direction and would entirely upset the timing of these operations. It is, for this reason, necessary to provide means for checking such backlash movement and the means illustrated comprises a pawl 115, rising from the shaft 40 to engage notches 116 in a disc 116. The latter rides on a stud 117 and a gear wheel 118 of this disc is in mesh with a gear pinion 119 of the mandrel shaft 20. At the time the clutch is released, it is found that the pawl engages a notch in the disc effectively to prevent such recoil rotation.

It is seen from the foregoing that I have provided a device which will automatically and at high speed produce continuous succession of in-

terwoven, flat, uniformly spaced coils. I do not, however, wish to be limited to the exact combinations and arrangements of parts and features, but reserve the right to embody modifications thereof within the scope of the claims hereto appended.

I claim:

1. A wire netting machine comprising, a frame, a slide lengthwise adjustable on said frame, a guide on said slide including two identical uniformly spaced interwoven helical coils, a second guide on the slide in axial spaced relation to said first guide and similarly composed of two identical uniformly spaced interwoven helical coils, a mandrel extending through said guides, means for feeding two strands of wire through the entrance to the spaces between the two first named guide coils on to said mandrel, means for rotating the mandrel continuously to draw the wires through the space between the coils of the two guides thereby to form two identical interwoven uniformly spaced coils of wire, means for relatively adjusting the coils of each of said guides, and means for clamping said slide in adjusted position on the frame.

2. A wire netting machine comprising, two guides in axially spaced relation to each other, each guide consisting of two identical uniformly spaced interwoven helical coils, a driven shaft, a chuck on the end of said shaft composed of two relatively angularly adjustable members, a mandrel seated in said chuck for rotation therewith, means for feeding two strands of wire through the entrance to the coil spaces of said first guide on to said mandrel, means for rotating said shaft and mandrel continuously to draw the wires on the mandrel through the spaces of said guides thereby to form two identical interwoven uniformly spaced coils of wire, a cut-off mechanism, means for adjusting the members of said chuck angularly to align the mandrel with the said cut-off mechanism, and means for relatively adjusting the two coils of each guide axially, and means for locking each coil in adjusted position.

3. A wire netting machine comprising, a frame, a slide lengthwise adjustable on said frame, two guides on said slide in axially spaced relation to each other, each guide consisting of two identical uniformly spaced interwoven helical coils, a driven shaft, a chuck on the end of said shaft composed of two relatively angularly adjustable members, a mandrel seated in said chuck for rotation therewith, means for feeding two strands of wire through the entrance to the coil spaces of the guide nearest said chuck on to said mandrel, means for rotating said shaft and mandrel continuously to draw the wires on to the mandrel through the spaces of said guides thereby to form two identical interwoven uniformly spaced coils of wire, a cut-off mechanism, means for angularly adjusting said chuck members correctly to align the mandrel angularly with said cut-off mechanism, means for relatively adjusting the two coils of each guide axially, means for locking each coil in adjusted position on the slide, and means for clamping said slide in adjusted position.

4. A wire netting machine comprising, a support, a guide in said support consisting of two identically shaped interwoven helical coils in axially spaced relation to each other, the support having axially elongated perforations through the wall thereof, bolts extending through said perforations and seated in said coils for clamping each of said coils in position in the support, the coils being relatively adjustable within the limits of said elongated perforations, a flat mandrel

extending through said guide, means for feeding two strands of wire through the entrance to the spaces between the two guide coils on to said mandrel, and means for rotating the mandrel to draw the wires through said spaces to form two identical flat interwoven uniformly spaced coils of wire.

5. A wire netting machine comprising, a support, a guide consisting of two identical interwoven helical coils seated in said support in axially spaced relation to each other for relative axial adjustment therein, means for clamping each of said coils in adjusted position within the guide, a driven shaft, a chuck on the end of said shaft, a flat mandrel seated in said chuck for rotation therewith and extending through the coils of said guide, means for feeding two strands of wire into said coil spaces, means for rotating the shaft and mandrel to draw the wires through

the coil spaces to form two identical flat interwoven uniformly spaced coils of wire about the mandrel, a cut-off mechanism, and means for angularly adjusting said chuck on the shaft to turn the mandrel into proper angular relation to said cut-off mechanism.
